(57) **CLAIM**

The ornamental design for a shoe as shown and described.

DESCRIPTION

FIG. 1 is a perspective view of a first embodiment of a shoe in a first configuration showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and

FIG. 7 is a rear elevational view thereof.

FIG. 8 is a perspective view of the shoe of FIG. 1 in a second configuration;

FIG. 9 is a left side elevational view thereof;

FIG. 10 is a right side elevational view thereof;

FIG. 11 is a top plan view thereof;

FIG. 12 is a bottom plan view thereof;

FIG. 13 is a front elevational view thereof; and,

FIG. 14 is a rear elevational view thereof.

The shoe illustrated in the figures is a right-footed form of the shoe. The broken lines formed by even length segments depict portions of the shoe that form no part of the claimed design. The broken lines formed by dash-dot-dash segments in the figures define a boundary of the claimed design and form no part thereof.
